UNITED STATES PATENT OFFICE.

HILARION DE ESCOBALES, OF BROOKLYN, NEW YORK, ASSIGNOR TO H. ESCOBALES CO. INC., OF NEW YORK, N. Y., A CORPORATION OF NEW YORK.

CIGARETTE-POUCH-PACKAGING MECHANISM.

Application filed February 4, 1921. Serial No. 442,404.

To all whom it may concern:

Be it known that I, HILARION DE ESCOBALLES, a citizen of the United States, and resident of Brooklyn, in the county of Kings 5 and State of New York, have invented certain new and useful Improvements in Cigarette-Pouch-Packaging Mechanism, of which the following is a specification.

My invention relates to mechanism for applying pouch, or cup, wrappers to cigarette packages, and more especially to mechanism which is adapted to be used as an attachment to existing machines which automatically supply, bunch and compress groups of 10 cigarettes of suitable number, wrap them in inner, or intermediate wrappers and then insert the packages so produced into separately formed paper "cups" or "pouches," which are placed by hand in position to receive the embryo, or partially wrapped packages, as they are successively ejected from the automatic machine.

The patent to Elberon D. Smith, No. 1,114,053, dated October 20, 1914, shows and 25 describes a wrapping machine of the class referred to; and a leading object of my invention is to provide automatic mechanism for applying cup-wrappers, suitable for attachment to such machine, including machines now in use and made in general accordance with the disclosure of the above-mentioned patent, although such machines may differ in certain respects, more or less, 30 from the exact structure disclosed in the patent.

The patented machine, as stated, requires cup-wrappers to be separately produced complete, and placed by hand on a "spout" through which the embryo packages are 35 pushed by an ejector, which then forces the cup wrapper with its contained cigarettes and intermediate wrapper from the spout, to be carried off by a conveyor. The machine is therefore limited in output to the rate at which an attendant can properly position the cup-wrappers.

My invention aims to increase the output-speed of such machines and to remove any limitation imposed by the stated hand operation, by automatically applying the cup-wrappers to the embryo packages; and preferably also, as in the present exemplifying embodiment, avoids the cost and other disadvantages incident to the separate produc-

tion and handling of the cup-wrappers by 55 automatically forming them.

A large number of machines of the patented type are in use, representing a high money value; and one important object of my invention is to provide mechanism having the desired functions in the form of an attachment, which can easily be applied to the existing machines with few and cheaply made changes, which do not involve anything approaching redesigning or rebuild- 60 65 ing such machines.

Complex problems are involved in the conception and practical embodiment of mechanism for attaining the desired objects, and especially in embodying such mechanism in 70 the form of an attachment to existing machines of the indicated type. Among these problems are the following:

The patented machine includes means for compressing a segregated group of cigarettes, placing and folding an intermediate wrapper about them, and maintaining the compression of the package during and after such wrapping, to prevent expansion of the package and dislocation of the wrapper, and finally the presentation of the package, with the wrapping operation practically completed, at a point where it is acted upon by the ejector, previously mentioned, to push it through the "spout," the compression of 75 80 85 the package being maintained at this, as well as previous positions. The space available at this position is small, and is circumscribed by various stationary and movable parts of the machine, and it is necessary to 90 arrange the attachment mechanism so that it will receive the packages at the position mentioned, maintain them in proper form, and perform the necessary operations of placing pouch-wrappers upon them and 95 preferably also of forming the wrappers, without interference with the existing mechanism, beyond the removal of superfluous parts, such as the spout referred to, and addition of few parts, such as driving and link connections, and similar minor alterations.

My invention provides a satisfactory solution of these problems.

In a packaging machine of the patented 105 type it is found that occasionally the mechanism for supplying a group of cigarettes to one of the pockets, or for supplying the in-

22 manner wrapping, or other parts of the mechanism fail to act properly, resulting in the absence of a package from one of the pockets as it approaches the point of discharge from the rotary table, or in the presentation of a defective package at this point. These occurrences would be sufficiently frequent, in the absence of means for taking care of this difficulty, to cause the waste of a substantial number of cup wrappers when my attachment mechanism is used with such a machine or to cause considerable difficulty from the improper feeding and accumulation of wrappers, some of which would not be used by reason of failure of a package to be delivered to the pouch applying mechanism consequent upon the stated failure of the main machine to deliver a package, or by the delivery of a defective package.

20 An important object of the present invention is to provide for such failures or imperfect operations of the patented machine, and this is accomplished by providing means for omitting the feed of a pouch wrapper at 25 a time properly corresponding to the position of the defective or omitted package in the main machine; consequently when there is a vacancy in the procession of packages fed to the pouch applying mechanism, corresponding to the omitted package, there is 30 a corresponding omission of a pouch wrapper at the initial wrapper applying position and waste of wrappers or difficulties consequent upon the supply of an unnecessary 35 number of wrappers are avoided.

This wrapper-sheet feed-controlling mechanism may vary greatly, and in the present embodiment of the machine I show only one exemplifying form (with certain modifications), consisting of a "detector" device 40 which becomes active upon the omission of a package, in the patented type of machine, and thereupon controls an electric circuit including a magnet to operate a clutch incorporated in the cup-wrapper sheet-feeding mechanism, so as to omit the feed of a wrapper at a time corresponding properly to the 45 position of the omitted package.

While my invention is desirably embodied 50 in the form of an attachment, for the reason stated, it is not necessarily so embodied; and from one point of view the invention may be regarded as a part of a complete machine for grouping and initially wrapping and 55 then automatically applying pouch wrappers to cigarette packages or the like. Evidently the novel structures of the present invention or suitable subordinate parts of it may be embodied in a machine of different 60 design from machines of the type of patent referred to. Certain features of the invention, parts and sub-combinations of parts are also available and valuable aside from the complete structure as hereinafter 65 described.

The characteristics and advantages of my invention are further sufficiently explained in connection with the following detail description of exemplifying embodiments of the invention, as shown in the accompanying 70 drawings. After considering these embodiments, it will be understood that many variations may be made in details and in combinations and sub-combinations of parts in accordance with the principles of the invention, and I contemplate the employment of any structures which are within the scope 75 of the claims.

In the accompanying drawings:

Fig. 1 is a plan view, partly in section, of 80 an attachment embodying my invention, showing sufficient parts of an existing wrapping machine to enable the connection and operation of the attachment in conjunction with said machine to be understood;

Fig. 2 is a front elevation with some parts 85 in section;

Fig. 3 is a right-hand end elevation;

Fig. 4 is a perspective view of an embryo 90 package in initial relation to a cup-wrapper sheet;

Fig. 5 shows the wrapper sheet partially folded about the package.

Fig. 6 shows additional steps in the folding.

Fig. 7 shows the complete cup wrapper placed upon the embryo package by the operations of my attachment mechanism.

Fig. 8 is a diagrammatic view from a 100 front elevation view-point of Fig. 1, showing the cup wrapper sheet feed and conveying mechanism, and illustrative of certain sheet positions therein.

Fig. 9 is an enlarged detail, in plan, of 105 package "detector" mechanism as applied to the initial wrapping machine.

Fig. 10 is a view, partly in elevation and partly in section, of the same.

Fig. 11 is an enlarged horizontal section 110 of a part of the cup wrapper sheet feed mechanism, showing mainly its clutch mechanism and clutch operating means.

Fig. 12 is an enlarged elevation-detail of the same.

Fig. 13 is a diagram of a modification of 115 the cup-wrapper control-feeding mechanism.

Fig. 14 is a detail plan view of the final package pressing and conveying channel.

Fig. 15 is a plan view with some parts 120 omitted of a modified embodiment of my attachment mechanism, in which the channel arrangement and the movement of the embryo packages are considerably simplified.

Existing machines of the class previously 125 referred to, as sufficiently exemplified for the present purpose by the structure shown in the previously identified patent to Smith, No. 1,114,053, comprise a rotary table 1 carrying a series of pockets 2, in which 130

groups of cigarettes of predetermined number are placed by suitable mechanism, in association with an initial or intermediate wrapper P (Figure 4). The table is intermittently rotated and finally a pocket 2 is brought to the position B in Figure 1, opposite a stationary supporting block 3 carried by a stationary table 4. At this position the packages, which will be defined in their present condition as "embryo" packages, are elevated between plates 5 and 6 beneath a horizontal plate 7, and the three plates 5, 6 and 7 are moved forward by a slide to which they are attached (not here shown), carrying the package in properly assembled and compressed condition over the upper surface of block 3 to a position where the package P, shown in dotted lines, is in front of an ejector plunger 8. As the package moves forward over the surface 3 the formation of the inner wrapper is complete, except that an end flap of the wrapper projects downward along the vertical face 9 of block 3, as shown in Figures 17 and 32 of the patent, a clearance being provided along said block face to permit the movement of said projecting flap. The ejector 8 now moves to the right in Figure 1 to move the embryo package into the open end of a spout, best shown in the patent in Figure 32, and in this movement the downwardly projecting flap of the package is smoothed over against the lower package side by the upper rounded edge of a block (283 in the patent). A separately-formed pouch wrapper (285 in the patent) was previously placed over the outer end of the spout, against a stop, and the ejector forces the embryo package through the spout and into the cup and then forces the completely pouch-wrapped package off of the spout onto a conveyor. The vertical plates 5, 6 and 7 at about this time return to the position shown in Figure 1, plate 6 being pivoted to its carrier to permit this return movement without interference with other parts.

The ejector 8 in the patented structure is carried by a plunger 10 which is in turn carried by slide 11, reciprocably mounted on a bar 12 secured to a bracket 13 fixed to table 4; and the slide is moved by a link 14 connected to a cam lever 15, the upper end of which extends through a slot 16 in the stationary table; and the cam lever is oscillated at suitable intervals in relation to other operative parts by a cam and driving connections, as fully explained in the patent.

The patented structure also includes a shaft, arranged in an upper, horizontal position, which carries a number of cams and other operative parts of the machine, and a fragment 17 of this shaft is shown in dotted lines in Figure 1.

A number of stationary and movable parts of the mechanism of the existing machine are, therefore, located in the neighborhood of the position in which the embryo package P is shown in Figure 1. My invention, devised in the present embodiment as an attachment to the described machine, is organized so that after the spout of the main machine, above referred to, is removed the attachment may be put in position practically without interference with the existing machine, except the addition of a very few and simple driving parts and connections, the attachment organization being adapted to the restricted space and other conditions existing in the main machine, some of these restrictions and limitations having been referred to previously, and the expedients of attachment and connections and other slight modifications of the existing machine being further sufficiently explained hereafter.

The attachment mechanism includes cup-wrapper applying mechanism D and transferring, or conveying mechanism, and preferably these principal instrumentalities are secured on a support or table, so that such mechanism, except minor connections, etc., constitutes a unit which may be easily attached to the initial packaging machine. The wrapper-applying mechanism is located in such a position that it will not conflict with stationary or operative parts of the main machine when the attachment is employed; and the conveying mechanism is arranged to transfer the embryo packages from their point of delivery by the main machine, to the cup-wrapper-applying mechanism; and to maintain the packages in properly-wrapped and compressed condition during transfer.

The cup wrapper applying mechanism may vary greatly. In the present embodiment the cup wrapper is presented in the form of a flat sheet or blank which is provided with adhesive as it moves to application position, and the wrapper is then applied to the advancing embryo package in properly registered position and is secured on the end of the package by the adhesive; the package and blank are then advanced together and the wrapper is folded about the package to form a complete cup wrapper, the parts of which properly adhere together by reason of the adhesive.

Similarly, the transfer or conveying mechanism may vary greatly and as shown in the present embodiment it is especially adapted to the particular type and location of cup wrapper applying mechanism and to other present conditions.

In the present embodiment the attachment mechanism is constructed and arranged as follows:

A supplemental table 20 is bolted to sta- 130

tionary table 4 and a part of this supplemental table runs alongside the edge 9 of block 3, providing clearance for the downwardly extending flap of the embryo assembly previously referred to, and being provided with a rounded edge 21 over which the lower side of the embryo package passes as it is advanced by ejector 8; and said edge and the upper surface of the table member at 10 this point smooth down the flap against the under side of the package, as in the operation of the patented structure. The spout previously referred to, which is located at this point, is removed and is replaced by a 15 package channel 22 composed of the table surface adjacent to edge 21 just mentioned, uprights 23 and a top plate 24, secured by screws 25 to the uprights. Communicating with this channel is a transverse channel 28, 20 the bottom of which is defined by the upper surface of table 20, the sides by upright members 29, and side top portions by plates 30 screwed to the uprights. A portion of plate 24 extends over channel 28 and forms a part 25 of its upper marginal portion, co-operating with the left hand plate 30. The stroke of ejector 8 carries the wrapped package to the position shown in dotted lines at P', where the right hand end of the package is against 30 the right hand upright 29 and the left hand end of the package is clear of channel 22 and the package is ready to advance laterally into channel 28.

During the described movement of the 35 package into the position P' it is kept in proper compression, with the initial or intermediate wrapper in proper folded position, by confinement in the passage 22 and then by the inwardly extending portions of 40 plates 30 and 24 which confine the ends of the package sufficiently to prevent any expansion or dislocation of the wrapper.

The packages are advanced successively 45 through the lateral channel 28 by a reciprocating pusher plate 32 shaped to conform approximately to the channel. This plate lies normally at the inner end of the channel slightly out of the path of movement of packages P', as shown in Figure 1. The pusher plate 32 is carried by an arm 33 secured to a 50 slide 34 moving in guides 35. The slide is reciprocated by a lever 36 fulcrumed at 37 on an upright 38 secured to the supplemental table and a link 39 connecting the lower end 55 of the lever to a bracket 40 on the slide. Mechanism for actuating the lever in properly timed relation to other parts of the mechanism will be described hereafter. By successive reciprocations of the feed plate 32 60 successive packages are advanced in close contact with each other and their compression is maintained until the foremost package reaches the outer end of channel 28, where it is held with sufficient firmness 65 against a stop plate 41 secured to the supple-

mental table by screws 42; and for convenience in the placing and removal of the stop plate it may be provided with slots 43, one of which may be L-shaped and the other straight, in its base, so that it may be quickly 70 put in place by an obvious co-operation of with the slots and the shanks of screws 42, and secured by tightening the screws. Right-hand channel upright 29 is cut away to provide a passage at 45 for the embryo packages 75 and the left-hand upright 29 is cut away at 46 to provide a passage for a feed plunger 47, mounted on a reciprocating rod 48 carried in guide members 49 secured to the table. Plunger 47 at each stroke advances a package 80 from the outer end of channel 28 to the mechanism for placing upon it a cup wrapper, by automatic operations, which will be presently described.

Rod 48 of plunger 47 is conveniently operated by connection with slide 11 of the existing machine in the following manner: A bracket 50 is secured to table 4 extending inward over the rotary table 1 of the machine, room being found for this bracket at the place indicated in the drawing. A lever 51 is fulcrumed at 52 on the inner end of the bracket and the lever is connected at 55 by a link 54 to a bracket 56 secured to slide 11 by screws 57. The outer end of the lever is connected at 58 to a link 59, which is in turn connected at 60 to a post 61 secured to rod 48. By means of lever 51 the motion of slide 11, which is just sufficient to give a proper stroke to ejector plunger 8, is multiplied and communicated to plunger 47 which has a stroke sufficient to carry it from the retracted position of Figure 1 into engagement with a package at the outer end of channel 28 and then to move the package all 100 the way through from the point where a cup wrapping paper is applied to the advancing end of the package to a point where the wrapper is partially folded about the package and the package is moved downward through a channel in which further and final wrapping operations are performed.

The initial wrapping channel extending horizontally at a right angle from the outer end of channel 28, extends past a slot 65 in the table through which the cup wrapper paper passes in front of each advancing package, and extends to the point 66, Figure 2, where the packages are in position to be moved downward through the vertical and final wrapping channel, defined by a depending frame member 67 secured to the under side of the supplemental table, and by plates 68, and associated devices later described.

Driving means are provided for suitable cup-wrapper-sheet-feeding, conveying and gumming mechanism and other parts of the attachment, including the following:

An upright or standard 70 is bolted on 120

table 20 in a position opposite upright 23 and a drive shaft 71 is supported in bearings 72 in these uprights. At a point on drive shaft 17, which is a principal operative part of the patented machine, as previously mentioned, room is found between other parts connected to said shaft for a drive sprocket 73, shown in dotted lines in Figure 1; and this is connected by a chain 74 to a sprocket 75 on attachment driving shaft 71. Shaft 71 provides means for driving the cup-wrapper-feeding, conveying and gumming mechanism, and certain parts of the package feeding and wrapping mechanism, as will appear.

Located on the supplemental table is wrapper sheet feeding, conveying and adhesive applying mechanism, certain suitable forms of which are more fully described in my previous applications, Serial No. 154,447, filed March 13, 1917, and Serial No. 429,696 filed December 10, 1920. The salient features of such mechanism will now be briefly described, reference being made to said applications for a more complete description of the mechanism; and certain additions to such sheet feeding mechanism, especially valuable in the present adaptation, will then be described.

A stack of cup wrapper sheets S is supported on a table 78 and the table is supported above supplemental table 20 by frame members 79 and 80. Uprights 80 provide bearings for a shaft 81, which is the drive shaft of the sheet feed and conveying mechanism, and is driven by bevel gears 82 from shaft 71. Adjacent to shaft 81 is a shaft 83 connected to shaft 81 by gears 84 and 85. Uprights 80 also carry a revoluble shaft 86 and the uprights are provided with extensions 87 supporting a shaft 88. Uprights 80 also support revoluble shafts 89, 90 and 91. Shaft 81 carries a conveyor roll 93 and co-operating with this are rolls 94 and 95 on shafts 86 and 88 respectively. The three rolls are provided with band grooves 96 in which are located continuous conveyor bands 97, conveniently of the close-coiled spring type. Shaft 83 carries a conveyor roll 99, usually of the same size as roll 93, and co-operating with this and a roll 100 carried by shaft 89 and idler rolls carried by shafts 90 and 91. The rolls last mentioned are provided with grooves near their ends corresponding in position to the grooves of rolls 93, 94 and 95, and in these grooves are located conveyor bands 106, substantially parallel to bands 97 and of similar form. The bands 106 and 97 provide two active conveyor flights 109, the upper portion of which is curved about roll 99 and a converging entrance is provided at 110 for sheets delivered from the bottom of stack S. Rolls 93 and 94 are also desirably provided with central grooves 112 in

which is located a central band for supporting the sheets adjacent to the gummer.

An oscillating feed frame comprising side members 115 and 116 connected by transverse rods 117 is pivoted on the axis of shaft 83 and this frame has an arm 120 provided with a cam roller 121 engaging the periphery of cam 122 on shaft 81. The frame also carries a rotatable shaft 124 connected to shaft 83 by means of gears 125, 126 and an idler gear 127. Shaft 124 carries a rubber-faced feed roll 130 adapted to be brought into contact with the lower sheet of the stack S when the feed frame is oscillated by cam 122.

In one form of the invention gear 126 may be fixed on shaft 124 and in that case the feed roll 130 is continually driven by the gear connections described from shaft 71, and at each contact with the sheet stack it feeds forward the lowermost sheet through a suitable aperture in the sheet supporting means and the forward edge of this sheet passes into the entrance 110 where it is grasped by the active flight of the conveyor bands and carried downward and discharged through an opening 132 in table 20 with its lower edge resting on a stop 133. The sheet is then free from the conveying mechanism and in position to be engaged by a package advanced by plunger 47, the package striking the center of the vertically supported sheet as shown in Figure 4. Support 133 is preferably provided with a vertical plate 134, and the table is provided with depending members 135, the plate and depending members providing spaced supporting guides for the lower part of the wrapper sheet, in which the sheet rests with suitable freedom. The support 133 is desirably adjustable as for example by providing it with an ear 137 secured to the upper end of a screw 138, which passes through separated lugs 139 on frame member 67 and is engaged by a knurled nut 140 located between the lugs so that by rotation of the nut the screw and the support may be adjusted vertically to properly position the sheet.

Adjacent to the active conveyor flight is gumming mechanism G (Figures 2 and 8) of any suitable type, including in this embodiment a roll 145, having raised peripheral portions spaced so as to apply to the wrapper sheet suitable strips a and a' of adhesive as indicated in Figure 4 and these raised portions of the roll are at the same time arranged so as to avoid conflict with the conveyor bands. Each sheet, therefore, is gummed as it passes through the conveyor, and suitable provision is made (consisting in this case of the relative arrangement of conveyor bands and gumming surfaces of roll 145) to prevent application of adhesive to the bands in the absence of a wrapper sheet.

In the normal operation of the machine, 130

6

each advancing movement of plunger 47 removes a package from the transverse channel into the position shown in Figure 4, with its advancing end against the center 5 of a wrapper sheet, as above stated. The embryo package and wrapper are thus brought into properly registered engagement and the proper positioning of the wrapper upon the package is maintained by 10 adhesion of the glue stripes previously applied to the bottom or advancing end of the embryo package. The proper position of the wrapper is so maintained during the subsequent folding operations. In the further movement of the plunger the package 15 and wrapper assembly are advanced between table surface 147 and a plate 148, and the wrapper sheet is folded so that portions s' and s^2 lie against upper and lower sides 20 of the package, and adhesive stripes a' are in contact with the end and sides of the package, as shown in Figure 5. End folds s^3 are then made by end-folding plates 150 having outwardly curved forward ends. 25 These plates are carried by stems 151 adjustably held by screws 152. Spaces are left for the passage of side flaps s^4 and s^5 between the upper and lower edges of the end-folding plates and plate 148 and the table 30 surface respectively. The package in the form shown in Figure 5 then comes to rest above the vertical folding channel and the plunger is retracted. The package here rests upon hinged plates 155 normally held 35 up by springs 156. Near the rear end of each of the plates 155 and near its inner edge, the upper surface of each plate is provided with a rounded projection 155a. These projections serve to apply added pressure 40 to sides of the package near its closed end as it descends between the plates; that is this added pressure is applied to firmly press down the creases at s^6 , Figure 7. Two side-folding plates 158 carried by a vertical 45 plunger 159 are then moved down and fold the flaps s^4 down against the narrow sides of the package, as shown in Figure 6. A plunger 160 connected to a vertically reciprocating rod 161 is then moved down upon 50 the upper face of the package and depresses the package between the hinged plates 155, which turn downward against their springs and fold up side flaps s^5 against the narrow 55 sides of the packages and over flaps s^4 , different portions of the adhesive strips a adhering to surfaces of the package and to surfaces of the pouch wrapper during the last described operations. The package is then substantially complete as shown in 60 Figure 7, the inner or embryo package P being enclosed in a completely formed pouch wrapper entirely enclosing the package except at one end, which is left exposed for ready access, by tearing, to the contained 65 cigarettes, as is desirable in packages of this

kind. The downward movement of plunger 160 moves the package substantially to the position of upper package P in the column of packages in the vertical folding and pressing channel, as best shown in Figure 3. Here the packages lie in flatwise contact, and are successively advanced between suitable devices for retaining and pressing the side flaps to insure proper adhesion of the gummed stripes, such device being represented in the present embodiment by endless belts 165, carried by rollers 166, which have shafts 167 mounted in bearings in depending frame members 67 and 68. Between the two flights of each belt are located spring-abutment plates 169, having end flanges 170 secured to the frame members by screws 171. Bearing against the inner active flights of the belts are pressure plates 175 pressed inward, to cause the inner belt flights to engage the package column with suitable pressure, by springs 176 supported from plates 169 by studs 177. The lowermost packages in the column are successively discharged upon a table 180, where the sides of the packages lie between adjustable blocks 180a to positively press the side folds of the packages. These blocks may be adjusted inwardly by screws 180b. These lowermost packages are then discharged laterally upon table 180 by a plunger 184 carried by a reciprocating rod 185, the brushes 181 in the discharge movement of the packages further pressing and smoothing down the side flaps. Instead of a discharge table 180 a suitable continuous conveyor may be provided, or the completed packages may be otherwise disposed of.

Suitable mechanism is provided for moving folding plates 158 and plunger 160, comprising in the present case the following:

Shaft 71 is provided with a circular cam body 188 having a cam groove 189 in which rests a cam roller 190 carried by a cam yoke 191, arranged to straddle the shaft, as best indicated in Figure 3. The outer end of this cam yoke is pivotally connected to the upper arm of a bell crank 194, fulcrumed at 195 on a part of one of the uprights 80. The end of the other arm of this bell crank is connected by a link 196 to a slide 197 mounted in guides 198 also suitably connected to upright 80. To this slide is connected plunger 159 previously mentioned, which carries the side-folding plates 158. Cam groove 189 is designed and positioned so that the side-folding plates are moved down just after the packages are placed upon hinged plates 155.

Shaft 71 also carries a cam body 200 having a cam groove 201 in which rests a cam roller 202, which is located on the long arm 203 of a bell crank fulcrumed on the same pin 37 which forms a fulcrum for lever 36

previously mentioned. The outer end of arm 203 is connected by a link 205 to the upper end of rod 161 previously mentioned, which carries plunger 160. Cam groove 201 is designed and arranged so that through the bell crank and linkage described the plunger 160 is moved down just after the action of folding plates 158. To additionally guide plunger 160, it is preferably provided with a head 207, Figure 2, to which rod 161 is connected and this head is also connected to another rod 208; and rods 161 and 208 reciprocate in suitable holes provided in a frame member 209.

5 15 Bell crank 203 above mentioned also has a short arm 215 connected by a link 216 to a lever 217 fulcrumed at 218 on a part of upright 38. The lower end of this lever is connected by a link 219 to lever 36 which operates transverse plunger 32; and the lever and link connection described is such that the movement of the short arm 215 of the bell crank is sufficient to give the necessary transverse feed movement to plunger 32.

20 25 The arrangement of the cam groove 201 is also such that the transverse plunger or feed plate 32 is moved at the proper time, shortly after a package has been placed in front of it by ejector plunger 8.

30 35 The final discharge plunger 184 is operated by an arm 221 connected to bar 48 which carries plunger 47. Arm 221 depends through a slot 222 in the supplemental table and has its lower end apertured to embrace plunger rod 185, which is slidably supported in sleeves 223, one of which is located on depending frame member 67 and the other is located on a strut connected to the supplemental table. Collars 224 are adjustably secured on rod 185 by set screws or like means and the end of arm 221 moves between these collars with suitable lost motion, so that when plunger 47 is retracted to the position shown in Figure 2, plunger 184 is retracted; and in the long feed movement of plunger 47 the clearance between arm 221 and the right hand collar 224 is first taken up and then plunger 184 is moved forward sufficiently to eject the lowermost package from the vertical folding and pressing channel; and then plunger 184 is retracted in the rearward movement of plunger 47, and so on.

40 45 The normal operation of my attachment mechanism has been described; that is, the operation desired in connection with the main machine when a package is properly formed in each pocket of the main machine and delivered in front of the ejector plunger. But as stated in the preamble there is a failure to present a package, or a properly formed and wrapped package, in a considerable number of cases and to take care of this peculiarity of the patented type of machine, my invention includes means for omitting the feed of a cup-wrapper sheet in ac-

cordance with such errors or failures of the main machine; and suitable embodiments of such mechanism will now be described.

50 55 In the description of the wrapper-sheet feed mechanism it was stated that gear 126 which drives the feed roll 130 might be fixedly connected to the roll shaft 124. In this case a sheet will be fed invariably at every revolution of cam 122. Preferably, however, the gear is mounted for relative rotation upon shaft 124, as shown in Figure 11, and the inner surface of the gear rim, is formed into a conical clutch surface 225, engaged by a cone clutch 226 carried by a sleeve 227 slidably mounted on an extension 80 of shaft 124, and connected to turn with the shaft by means of a pin 229, and slot 228 formed in the sleeve. The clutch sleeve is provided with collars 230, forming between them an annular groove engaged by 85 a forked clutch-shifting arm 231, Figures 11 and 12. This arm is connected to the outer ends of rods 234, which reciprocate in sleeves 235 mounted on a plate 236 connected to one of the side members 115 of 90 the oscillating feed frame. On this plate are also secured one, or in the present case two, electro magnets 240, and clutch shifter arm 231 is provided with an armature plate 241, the ends of which are adjacent to the 95 ends of the magnet cores 242. Springs 243 located in the bottoms of sleeves 235 and acting on the inner ends of rods 234, normally hold clutch 226 out of engagement; and the clutch is engaged whenever the magnets are energized. This clutch engagement is effected whenever a package is properly located on rotary table 1 of the main machine, at a suitable point of approach of the table to package-discharge position. Suitable detector mechanism is provided to act in connection with the clutch mechanism, comprising in the present embodiment the following: The patented type of machine is provided with a presser plate 245 (233 in the patent) overlying pockets 2 at the position A, Figure 1, and extending substantially from that position to points near the last previous pocket position and the subsequent position B, which is the discharge position 100 of the main machine, this plate serving to press down and hold in position the packages in the pockets during their travel to and past the position A up to the position B. The presser plate 245 is carried by arms 105 246 pivoted at 247 at a fixed point on table 4 as best shown in Figure 2 of the patent. Arms 246 are connected to a plate 247' which in turn is connected to the pressure plate 233. I provide a frame member 250 arranged to 110 straddle arms 246 and provided with angular feet 251 secured to plate 247 by screws 252 passing through the plate and engaging plate 233. The frame 250 has a cross member 254 and a top member 255. 115 120 125 130

Plate 233 is cut out to provide a socket 260 accommodating a "detector," or feeler-head 261, the lower surface of which normally lies slightly below the under face of plate 233. This detector head is carried by a stem 262 passing through a suitable guide hole in plate 247 and another suitable hole in frame cross-piece 254. A collar 265 is adjustably connected to the stem above plate 247 by a set screw 266, to adjustably limit the downward movement of head 261. The head is urged downward by a spring 267 of moderate strength, located between the collar 265 and cross piece 254. The upper end of stem 262 carries a contact point 270 secured by a nut 271 and insulated by suitable means such as a washer 272, and a suitable flexible conductor wire 273 is connected to the contact point, conveniently by clamping it under nut 271. A stationary contact point 275 is carried by frame member 255, and is provided with suitable adjusting means and suitable insulating as for example washer 276 and sleeve 277; and to this contact point 25 is connected by a nut 278, a conductor wire 279.

Conductors 273 and 279 are in circuit through the magnets 240 as best indicated in Figure 12 and in the circuit is a suitable source of electrical energy, represented by a battery 281.

As a pocket 2, containing a properly formed package, approaches the station A, Figure 1, the upper surface of the package 35 slides under detector head 261 and moves it up and closes the electric circuit at contacts 270-275; magnets 240 are energized, and clutch 226 is engaged and gear 126 is rotatably connected with shaft 124, whereupon feed roll 130 is rotated at the same time that it is brought into engagement with the lower sheet of stack S by the action of a cam 122, to cause the proper feeding of a pack-cup wrapper sheet. But if there is no package in the pocket at station A, or if the package is incompletely filled the detector head 261 is not raised sufficiently to close the magnet circuit; clutch 226 is held out by springs 243 and no wrapper is fed. This feed omission must be properly related to the entire procession of packages from position A to the point of discharge from the main machine and in the feed channels of the attachment mechanism. The essentials 55 of this relation are sufficiently understood by mention of the fact that, with package and sheet-feed mechanisms arranged substantially as in the present embodiment, at the time a skip in the sheet-feed occurs, one or more, usually two, wrappers have already been advanced by the feed mechanism, corresponding to previous perfect packages advanced by the rotary table and subsequent package-feed mechanism. One of these two 65 wrappers is being located as shown in Fig-

ure 8, on support 133, ready to be folded about the next advancing package, and the other is somewhere in the active flight of the conveyor bands. The package-feed omission occurring at the station A, with 70 wrapper sheets in the positions indicated in Figure 8, the wrapper that has already been started through the conveyor flight will be properly fed into position on the support 75 133 and will be placed before the next advancing package. The sheet-feed skip then occurs at the same time that there is a skip in the feed of a package at the outer end of the lateral channel in front of plunger 47. There is considerable latitude in the relation of the detector to the table of the main machine and a corresponding latitude in the relation of the accurate skip in feed of the attachment mechanism to the package omission of the main machine. This will be understood by mention of the fact that omission of a sheet traveling in the conveyor bands toward the application point need not occur at the identical time that advancing 80 plunger 47 is not confronted by a package 85 in the transverse channel 28, for the conditions will be satisfied if a wrapper sheet is supplied at that time and the next one is omitted, since the wrapper sheet so supplied will remain in position until a package, is 90 fed against it by plunger 47; and a wrapper sheet following the "skip" position will then arrive in position at the proper time to be engaged by the next advancing package corresponding to the package following 95 the actual skip in the package feed. 100

The action of this mechanism in the present specific arrangement is more particularly explained as follows: Let it be assumed that in the position of parts shown in Figure 1 a properly filled pocket 2 has been placed by table 1 at the station B and the pocket at A is empty due to failure of the main machine mechanism to supply the proper package in previous positions of the table. The package is moved up from the pocket at B and moved in front of plunger 8 by plates 5 and 6. At about this time the wrapper sheet feeding mechanism (Figure 8) has placed a wrapper 105 at the position X and another wrapper has just been fed from the stack S and has reached approximately the position Y and is moving down between the active flights of the conveyor bands. Plunger 8 then moves the cigarette package into the first position 110 of the transverse channel 28; lateral feed plate 32 moves the column forward in the channel, and immediately thereafter plunger 47 moves the outermost package from the channel into engagement with the sheet at X and on toward the vertical folding channel. The plungers are all retracted again to the 115 position shown in Figure 1; the rotary table moves one step to bring the empty pocket 2 to the position B; the elevating mechanism 120 130

operates, and plates 5 and 6 move forward "empty," and no package is deposited in front of plunger 8. During the time the empty pocket was at the station A the detector mechanism operated as previously described to omit the feed of a sheet from the stack during one action of cam 122. At about the time that the feed plungers are ready to operate, the sheet which was at the station Y, Figure 8 has reached the station X and no sheet has issued from the stack to approximately the Y position, on account of the skip in the feed operation. The plungers then act as usual in a package feeding operation, but there is no package fed, due to the absence of the package in front of plunger 8 which creates a corresponding vacancy in front of plungers 42 and 27 as they act in turn. The sheet at the station X therefore, remains in position and at the next feed operation, assuming that a filled pocket followed the empty pocket on table 1, the packages are fed as usual and the sheet located at the station X is applied to the advancing packages. Another sheet has in the meantime been fed from the stack and has now reached substantially the position Y and will reach the position X in time for the next package, and so on, as long as the rotary table pockets are properly filled. The action corresponding to the omission of only one package has been described, but it will be evident from the foregoing that if two packages or more are omitted from the table pockets in succession there will be two or more skips in the pouch-wrapper feed operation, corresponding to the number of omitted packages.

The detector mechanism described need not necessarily be employed in connection with the sheet feed omitting mechanism. The operator may observe the condition of packages advancing toward the position of cup wrapper application, and when a defective package is noted, he may operate the clutch 226 by suitable mechanical means, or by pressing a button inserted in the electric circuit 279, whereupon the feed of a wrapper will be omitted, as sufficiently explained above.

Figure 13 shows diagrammatically a somewhat modified arrangement of the wrapper sheet feed controlling mechanism. In this arrangement the clutch 226 is held normally in engagement by a spring 285 acting on a shifting lever 286 fulcrumed at 287. The detector head 261 or a member connected with it is arranged to be supported between pockets 2 by a rail 288 properly located on table 1. Detector stem 262 carries an insulated contact 290 co-operating with a fixed contact 291. Magnet or magnets 240 are arranged to attract an armature on the adjacent end of shifting lever 286. The circuit remains open and the clutch

remains in engagement while the detector head is held up by rail 288 or by a package P properly located in the pocket 2 at the position A of Figure 1; but whenever a package is omitted the detector head will drop somewhat into the pocket, sufficiently to close the circuit, energize the magnet and withdraw the clutch to cause a skip in the wrapper sheet feed as before described. In this arrangement the magnet circuit 5 is open, except when there is a skip in package presentation, with a corresponding economy of electrical energy.

Many other arrangements of mechanical as well as electrical devices may be used for the sheet feed control and the ones here particularly described are intended, in the broader aspect of the invention, only as examples of suitable means for this purpose.

Figure 15 shows a general organization of the attachment mechanism which is considerably simplified and desirable in many cases. The forward transfer plate 6 shown in Figure 1, of the existing type of machine, is omitted, and the initially wrapped packages are advanced by plate 5 over table surface 3, under the upper plunger, into the entrance of a package channel 300 composed of side plates 302 and upper plates 304 which project somewhat over the ends of the packages. A package P is shown in the position in which it lies in this channel at the end of its movement from the main machine. As the packages commence to move toward the channel 300, their initial wrappers have projecting end flaps, and in the existing machine a curved folding member 306 is provided to fold up this flap at one end of the embryo package. For the purposes of my invention, this folding member is duplicated at 308 to provide for the folding of the other end flap up against the adjacent end of the embryo package. Plunger 8 of the existing machine, as previously described, is omitted, but a portion of the bar 12, and the bracket 56 for the operation of that plunger are retained. Successive movements of the transfer mechanism cause the packages P to advance through channel 300 to a point where they are opposite a short longitudinal channel 310 comprising side members 312 and a top plate 314, and the right-hand side member 302 of channel 300 is apertured to permit the packages to pass endwise into the short channel 310 and from that channel to the passage, 120 in which aperture 65 is provided for the positioning of the pouch wrapper blanks, as in the previous embodiment of the invention. Plunger 47 in this case is positioned to move a package from the outward end of channel 300 directly through channel 310 to the pouch wrapper applying mechanism, which acts as in the previous embodiment of the invention. The pouch wrapper applying mechanism is omitted in Figure 15 for the 130

sake of simplicity, but it may be substantially as in the previous embodiment, with the exception of devices for moving the lateral plunger 32 employed in that embodiment of the invention. Bolt holes 315 are shown in the supplemental table 20 for the connection of the pouch wrapper applying mechanism. The fulcrum point 53 of lever 51 is moved outward somewhat to provide the necessary longer stroke of plunger 47. In this simplified embodiment of the invention the longitudinal movement of the embryo packages after they are brought out by plate 5 and associated parts is dispensed with, and the packages simply move straight out in line with the original delivery movement of the machine and are then moved once at a right angle to the first line of movement, for the application of pouch 20 wrappers.

It will be understood from the foregoing description that my attachment mechanism provides cup wrapper applying mechanism conveniently located in relation to a main packaging machine, and means (consisting particularly, in this embodiment, of the longitudinal and transverse feed channels and the feed plungers), for maintaining the packages delivered by the main machine in proper condition of compression and with their initial or intermediate wrappers maintained in proper positions about the group of cigarettes, from the point of delivery from the main machine to the time of application of the cup wrappers.

Other suitable mechanism may be provided for transferring or conveying the packages from the main machine to the cup wrapper applying mechanism, and another 40 specific form of such mechanism which also embodies the important features of maintaining the packages in proper condition during transfer is shown in a companion application; and certain of the broader 45 claims herein cover such alternative transfer mechanism, as well as many other structures, combinations and sub-combinations of parts, which are equivalent to structures described in the present claims; and I do not limit myself to details, except as particularly pointed 50 out in the claims following.

What I claim is:

1. Mechanism for applying pouch wrappers to embryo cigarette packages and arranged for co-operation with a cigarette packaging machine comprising an intermittently-moving rotary horizontal mold table provided with pockets in which the embryo packages are formed and means for moving the completed embryo package from the pockets at one station to a delivery point, said mechanism comprising means for applying pouch wrappers to the successive embryo packages, means for folding the embryo packages, means for 65 wrapping the embryo packages into pouch form about the pack-

ages, and means arranged for connection with an operative part of said machine for moving the embryo packages from said delivery point to said pouch wrapper applying means.

2. Mechanism for applying pouch wrappers to embryo cigarette packages and arranged for co-operation with a cigarette packaging machine comprising an intermittently-moving rotary horizontal mold table 75 provided with pockets in which the embryo packages are formed and means for moving the completed embryo package from the pockets at one station to a delivery point, said mechanism comprising means for gumming and applying successive pouch wrappers to successive embryo packages, and means for transferring the embryo packages from said delivery point of the packaging machine to said applying means.

3. Mechanism for applying pouch wrappers to embryo cigarette packages and arranged for co-operation with a cigarette packaging machine comprising an intermittently-moving rotary horizontal mold table 90 provided with pockets in which the embryo packages are formed and means for moving the completed embryo package from the pockets at one station to a delivery point, said mechanism comprising means for gumming and applying successive pouch wrappers to successive embryo packages, means for forming the pouch wrappers about the embryo packages, and means for transferring the embryo packages from said delivery point of the packaging machine to said applying means.

4. Mechanism for applying pouch wrappers to embryo cigarette packages and arranged for co-operation with a cigarette packaging machine comprising an intermittently-moving rotary horizontal mold table 105 provided with pockets in which the embryo packages are formed and means for moving the completed embryo package from the pockets at one station to a delivery point, said mechanism comprising a base adapted for connection to said packaging machine and mechanism mounted on said base including pouch wrapper feeding and positioning means, a conveyor channel leading from the delivery point of said machine to said positioning means, package impelling means arranged for connection with an operative part of said machine for moving successive embryo packages through said channel, and means for folding successively positioned wrappers in pouch form upon successive embryo packages.

5. Mechanism for applying pouch wrappers to embryo cigarette packages and arranged for co-operation with a cigarette packaging machine comprising an intermittently-moving rotary horizontal mold table 125 provided with pockets in which the embryo

- packages are formed and means for moving the completed embryo package from the pockets at one station to a delivery point, said mechanism comprising means for applying pouch wrappers to the successive embryo packages, means for folding the wrappers into pouch form about the packages, and means arranged for connection with an operative part of said machine for moving the embryo packages from said delivery point to said pouch wrapper applying means, said last named means including a channel adapted to contain a series of the embryo packages.
6. Mechanism for applying pouch wrappers to embryo cigarette packages and arranged for co-operation with a cigarette packaging machine comprising an intermittently-moving rotary horizontal mold table provided with pockets in which the embryo packages are formed and means for moving the completed embryo package from the pockets at one station to a delivery point, said mechanism comprising means for gumming and applying successive pouch wrappers to successive embryo packages, and means for transferring the embryo packages from said delivery point of the packaging machine to said applying means, said last named means including a channel adapted to contain a series of the embryo packages.
7. Mechanism for applying pouch wrappers to embryo cigarette packages and arranged for co-operation with a cigarette packaging machine comprising an intermittently-moving rotary horizontal mold table provided with pockets in which the embryo packages are formed and means for moving the completed embryo package from the pockets at one station to a delivery point, said mechanism comprising means for gumming and applying successive pouch wrappers to successive embryo packages, means for forming the pouch wrappers about the embryo packages, and means for transferring the embryo packages from said delivery point of the packaging machine to said applying means, said last named means including a channel adapted to contain a series of the embryo packages, and also adapted to maintain the wrapper formations of the embryo packages during advance movement.
8. Mechanism for applying pouch wrappers to embryo cigarette packages and arranged for co-operation with a cigarette packaging machine comprising an intermittently-moving rotary horizontal mold table provided with pockets in which the embryo packages are formed and means for moving the completed embryo package from the pockets at one station to a delivery point, said mechanism comprising a base adapted for connection to said packaging machine and mechanism mounted on said base including pouch wrapper feeding and positioning means, a conveyor channel leading from the delivery point of said machine to said positioning means, said channel being of a length to contain a plurality of the embryo packages, package impelling means arranged for connection with an operative part of said machine for moving successive embryo packages through said channel, and means for folding successively positioned wrappers in pouch form upon successive embryo packages.
9. Cigarette packaging mechanism comprising a rotary table having a series of pockets in which initially wrapped embryo packages are presented at a delivery point, means for moving the embryo packages away from the pockets at said delivery point, a channel arranged to receive the packages as they are so moved and to accommodate a series of the packages, means for moving the packages successively endwise from the discharge end of said channel, and means for automatically presenting wrapper sheets in front of the packages so advanced and for shaping the wrappers in pouch form about the embryo packages.
10. The combination with a cigarette packaging machine in which initially wrapped embryo packages are presented by a rotary pocketed table successively at a delivery point and the embryo packages are moved laterally away from the pockets, of automatic pouch wrapping mechanism comprising a conveyor channel arranged to receive the packages as they are moved from the pockets and to contain a series of the packages and maintain their wrapped formation, means for discharging the packages successively endwise from the end of said channel, means for presenting pouch wrappers in front of the advancing embryo packages, and means for folding the wrappers into pouch form upon the packages.
11. The combination with means for successively advancing and initially wrapping groups of cigarettes or similar articles and delivering the successive initially wrapped packages at a discharge point, of means for successively presenting cup wrappers for application to said packages and means for omitting the presentation of a cup wrapper in a definite relation to the omission of a package by the initial wrapping mechanism.
12. In machine for packaging cigarettes and like articles, means for wrapping successive groups of cigarettes and delivering the initially wrapped packages successively at a discharge point, means for automatically applying cup wrappers to the packages, and means for omitting a cup wrapper in definite relation to the omission of an initially wrapped package.
13. In machine for packaging cigarettes and like articles, the combination with means for grouping and wrapping successive ciga-

ettes to form a succession of initially wrapped packages, of means for automatically applying pouch wrappers to said packages, of means for detecting the omission of an initially wrapped package, and means operating in conjunction with the detecting means and in definite relation to the operation of the grouping and wrapping means and the pouch wrapper applying means to cause a corresponding omission in the operation of the last named means.

14. Cigarette packaging mechanism comprising means for forming and advancing embryo packages past different stations to a discharge point, means for automatically applying cup wrappers to embryo packages, said means comprising means for feeding cup wrappers successively, means for detecting the omission of a package at a station anterior to said discharge point, and means operating in conjunction with said detecting means for producing a skip at a point in the succession of cup wrappers in proper relation to the location of the position of said detector with respect to said discharge point and operative characteristics of said transferring means.

15. The combination with a machine for forming embryo cigarette packages and moving them past several stations to a discharge point, of automatic cup-wrapper applying means operated in connection with said machine and including means for intermittently feeding a series of cup wrappers at a point for application to the embryo packages, means for transferring the embryo packages from said discharge point to said point of application and arranged to operate in timed relation to said machine, and means acting upon the omission of an embryo package by said machine to omit a cup wrapper at a proper point in the series fed by said cup-wrapper applying means.

16. The combination with a machine for forming embryo cigarette packages and moving them past several stations to a discharge point, of automatic cup-wrapper applying means operated in connection with said machine and including means for intermittently feeding a series of cup wrappers at a point for application to the embryo packages, means for transferring the embryo packages from said discharge point to said point of application and arranged to operate in timed relation to said machine, and means acting upon the omission of an embryo package by said machine to omit a cup wrapper at a proper point in the series fed by said cup-wrapper applying means, said cup wrapper omitting means comprising a detector acting at a certain of said stations and electrical means acting in connection with this detector to effect the operation of said cup wrapper applying means.

17. The combination with a machine for

forming embryo cigarette packages and moving them past several stations to a discharge point, of automatic cup-wrapper applying means operated in connection with said machine and including means for intermittently feeding a series of cup wrappers at a point for application to the embryo packages, means for transferring the embryo packages from said discharge point to said point of application and arranged to operate in timed relation to said machine, and means acting upon the omission of an embryo package by said machine to omit a cup wrapper at a proper point in the series fed by said cup-wrapper applying means, said cup wrapper omitting means comprising a detector located at one of said stations, an electric circuit controlled by said detector, an electro-magnet in said circuit and a clutch operated by the electro-magnet to effect the cup-wrapper omission.

18. Cup wrapper applying mechanism arranged as an attachment for a cigarette packaging machine in which initially wrapped cigarette packages are successively delivered, said mechanism comprising means for automatically gumming and applying cup wrappers to successive packages delivered by said machine.

19. Cup wrapper applying mechanism arranged as an attachment for a cigarette packaging machine in which initially wrapped cigarette packages are successively delivered, said mechanism comprising means for automatically applying cup wrappers to successive packages delivered by said machine, and means for folding the wrappers into complete cup form about the packages.

20. Cup wrapper applying mechanism arranged as an attachment for a cigarette packaging machine in which initially wrapped cigarette packages are successively delivered, said mechanism comprising means for automatically applying cup wrappers to successive packages delivered by said machine, means for transferring the packages from the machine discharge point to said cup-wrapper applying means, and means for folding the wrappers, by successive operations into complete cup form about the packages.

21. Cup wrapper applying mechanism arranged as an attachment for a cigarette packaging machine in which initially wrapped cigarette packages are successively delivered, said mechanism comprising means for automatically gumming and applying cup wrappers to successive packages delivered by said machine, and means for transferring the packages from the machine discharge point to said cup-wrapper applying means.

22. Cup wrapper applying mechanism arranged as an attachment for a cigarette packaging machine in which initially

- wrapped cigarette packages are successively delivered, said mechanism comprising means for automatically gumming and applying cup wrappers to successive packages delivered by said machine, means for transferring the packages from the machine discharge point to said cup-wrapper applying means, and means for folding the wrappers by successive operations into complete cup form about the packages.
23. Cup wrapper applying mechanism arranged as an attachment for a cigarette packaging machine in which initially wrapped cigarette packages are successively presented at a discharge point, said attachment mechanism comprising means for automatically gumming and applying cup wrappers to the successive packages, and means for transferring the packages successively from the discharge point of the packaging machine to said cup-wrapper applying means and maintaining the initially wrapped packages in proper condition during the transfer.
24. Cup wrapper applying mechanism arranged as an attachment for a cigarette packaging machine in which initially wrapped cigarette packages are successively presented at a discharge point, said attachment mechanism comprising means for automatically applying cup wrappers to the successive packages, means for transferring the packages successively from the discharge point of the packaging machine to said cup-wrapper applying means and maintaining the initially wrapped packages in proper condition during the transfer, and means for folding the wrappers into complete cup form about the packages.
25. The combination with a machine for forming and initially wrapping and successively delivering cigarette packages at a discharge point, of means for automatically applying cup wrappers to successive packages delivered by said machine, and means for forming said wrappers into complete cup-wrapper enclosures for the packages.
26. The combination with a machine for forming and initially wrapping and successively delivering cigarette packages at a discharge point, of means for automatically gumming and applying cup wrappers to successive packages delivered by said machine.
27. The combination with a machine for forming and initially wrapping and successively delivering cigarette packages at a discharge point, of means for automatically gumming and applying cup wrappers to successive packages delivered by said machine, and means for forming said wrappers into complete cup-wrapper enclosures for the packages.
28. The combination with a machine for forming and initially wrapping and successively delivering cigarette packages at a discharge point, of means for automatically gumming and applying cup wrappers to successive packages delivered by said machine, means for transferring the packages from the discharge point of said machine to said cup-wrapper applying means, and means for folding the wrappers by successive operations into complete cup form about the packages.
29. The combination with a machine for forming and initially wrapping and successively delivering cigarette packages at a discharge point, of means for automatically gumming and applying cup wrappers to successive packages delivered by said machine, and means for transferring the packages from the discharge point of said machine to said cup-wrapper applying means, and means for forming said wrappers into complete cup-wrapper enclosures for the packages.
30. The combination with a machine for forming and initially wrapping and successively delivering cigarette packages at a discharge point, of means for automatically gumming and applying cup wrappers to successive packages delivered by said machine, means for transferring the packages from the discharge point of said machine to said cup-wrapper applying means, and means for folding the wrappers by successive operations into complete cup form about the packages.
31. The combination with a machine for forming and initially wrapping and successively delivering cigarette packages at a discharge point, of means for automatically gumming and applying cup wrappers to successive packages delivered by said machine, and means for transferring the packages from the discharge point of said machine to said cup-wrapper applying means, and for maintaining the packages in form during transfer.
32. The combination with a machine for forming and initially wrapping and successively delivering cigarette packages at a discharge point, of means for automatically applying cup wrappers to successive packages delivered by said machine, means for transferring the packages from the discharge point of said machine to said cup-wrapper applying means and for maintaining the packages in form during transfer, and means for folding the wrappers by successive operations into complete cup form about the packages.
33. The combination with a machine for forming and initially wrapping and successively delivering cigarette packages at a discharge point, of means for automatically gumming and applying cup wrappers to successive packages delivered by said machine, means for transferring the packages from the discharge point of said machine to said cup-wrapper applying means and for maintaining the packages in form during transfer, and means for folding the wrappers by

successive operations into complete cup form about the packages.

34. Cup wrapper applying mechanism arranged as an attachment for a cigarette packaging machine in which initially wrapped cigarette packages are successively delivered, said mechanism comprising a base attachable to a stationary part of said machine, automatic cup-wrapper applying mechanism on said base, means for transferring packages successively from the delivery point of said machine to said cup-wrapper applying mechanism, and means for folding the wrappers into complete cup form about the packages.

35. Cup wrapper applying mechanism arranged as an attachment for a cigarette packaging machine in which initially wrapped cigarette packages are successively delivered, said mechanism comprising a base attachable to a stationary part of said machine, automatic cup-wrapper gumming and applying mechanism on said base, means for transferring packages successively from the delivery point of said machine to said cup-wrapper applying mechanism, and driving connections from operative parts of said machine to said cup-wrapper applying mechanism and said transferring means.

36. Cup wrapper applying mechanism arranged as an attachment for a cigarette packaging machine in which initially wrapped cigarette packages are successively delivered, said mechanism comprising a base attachable to a stationary part of said machine, automatic cup-wrapper applying mechanism on said base, means for transferring packages successively from the delivery point of said machine to said cup-wrapper applying mechanism, means for folding parts of said cup wrapper successively about the package to form a complete cup wrapper enclosure, and driving connections from operative parts of said machine to said cup-wrapper applying mechanism and said transferring means.

37. Cup wrapper applying mechanism arranged as an attachment for a cigarette packaging machine in which initially wrapped cigarette packages are successively delivered, said mechanism comprising a base attachable to a stationary part of said machine, automatic cup-wrapper applying mechanism on said base, means carried by said base for transferring packages successively from the delivery point of said machine to said cup-wrapper applying mechanism, and means for folding the cup wrapper into complete cup form about the packages.

38. The combination with a cigarette packaging machine having means for preparing a succession of initially wrapped cigarette packages and means for delivering the packages successively before an ejecting plunger,

of means for automatically applying cup wrappers to successive packages, means for transferring the packages successively from the ejecting plunger to the cup wrapper applying means and maintaining the form and compression of the packages during transfer, and means for folding the cup wrapper into complete cup form about the packages.

39. The combination with a cigarette packaging machine having means for preparing a succession of initially wrapped cigarette packages and means for delivering the packages successively before an ejecting plunger, of means for automatically applying cup wrappers to successive packages and means for transferring the packages successively from the ejecting plunger to the cup wrapper-applying means and maintaining the form and compression of the packages during transfer, means for folding the cup wrappers into complete cup form about the packages, and an operative connection between a part of said transferring means and the plunger operating mechanism of said packaging machine.

40. The combination with a cigarette packaging machine comprising means for forming and initially wrapping successive cigarette packages, and including an operating shaft, of means for automatically applying cup-wrappers to successive packages delivered from said machine, means for transferring the packages from the packaging machine to the cup wrapper applying means, means for folding the cup wrappers into complete cup form about the packages, and an operative connection from said shaft to said cup-wrapper applying means.

41. The combination with a cigarette packaging machine comprising means for forming and initially wrapping successive cigarette packages and presenting them at a delivery point, and including a rotary table, a stationary table, an ejecting plunger and an operating shaft, of means for automatically applying cup wrappers to successive packages delivered by said machine in front of the ejecting plunger, means for transferring the packages from the delivery point of the ejecting plunger to the cup wrapper applying means, said transferring means being constructed and arranged to maintain the packages in proper form for application to the cup wrappers, and means for folding the cup wrappers into complete form about the packages.

42. The combination with a cigarette packaging machine comprising means for forming and initially wrapping successive cigarette packages and presenting them at a delivery point, and including a rotary table, a stationary table, an ejecting plunger and an operating shaft, of means for automatically applying cup wrappers to successive packages delivered by said machine in

- front of the ejecting plunger, means for transferring the packages from the delivery point of the ejecting plunger to the cup wrapper applying means, said transferring 5 means being constructed and arranged to maintain the packages in proper form for application of the cup wrappers, and means for folding the cup wrappers into complete cup form about the packages, said cup 10 wrapper applying, transferring and folding means being located on a supplemental table arranged to be secured to the stationary table of said packaging machine.
43. The combination with a cigarette 15 packaging machine comprising means for forming and initially wrapping successive cigarette packages and presenting them at a delivery point, and including a rotary table, a stationary table, an ejecting plunger 20 and an operating shaft, of means for automatically applying cup-wrappers to successive packages delivered by said machine in front of the ejecting plunger, means for transferring the packages from the delivery 25 point of the ejecting plunger to the cup wrapper applying means, said transferring means being constructed and arranged to maintain the packages in proper form for application to the cup wrappers, means for 30 folding the cup wrappers into complete cup form about the packages, said cup wrapper applying, transferring and folding means being located on a supplemental table, arranged to be secured to the stationary table 35 of said packaging machine.
44. The combination with a cigarette packaging machine comprising means for forming and initially wrapping successive cigarette packages and presenting them at a delivery point, and including a rotary 40 table, a stationary table, an ejecting plunger and an operating shaft, of means for automatically applying cup wrappers to successive packages delivered by said machine in front of the ejecting plunger, means for 45
- transferring the packages from the delivery point of the ejecting plunger to the cup wrapper applying means, said transferring means being constructed and arranged to maintain the packages in proper form for 50 application of the cup wrappers, and means for folding the cup wrappers into complete cup form about the packages, said cup wrapper applying, transferring and folding means being located on a supplemental table, arranged to be secured to the stationary table of said packaging machine.
45. The combination with a cigarette packaging machine comprising means for forming and initially wrapping successive cigarette packages and presenting them at a delivery point, and including a rotary table, a stationary table, an ejecting plunger and an operating shaft, of means for automatically applying cup wrappers to successive packages delivered by said machine in front of the ejecting plunger, means for transferring the packages from the delivery point of the ejecting plunger to the cup wrapper applying means, said transferring 60 means being constructed and arranged to maintain the packages in proper form for application to the cup wrappers, and means for folding the cup wrappers into complete cup form about the packages, said cup wrapper applying, transferring and folding means being located on a supplemental table, arranged to be secured to the stationary table of said packaging machine, said cup wrapper applying mechanism including a 65 shaft connected with the operating shaft of said packaging machine, and operative connections between the shaft of said cup wrapper applying mechanism and parts of said transferring mechanism.
- Signed at New York city, in the county of New York, and State of New York, this 22nd day of December, A. D. 1920.

HILARION DE ESCOBALES.
